Primary Examiner — Amber R Stiles*Assistant Examiner* — Kellianne M Shaver(74) *Attorney, Agent, or Firm* — Hoffmann & Baron, LLP(57) **CLAIM**

The ornamental design for a cooler as shown and described.

DESCRIPTION

FIG. 1 is a top perspective view of a cooler showing my new design;

FIG. 2 is a bottom perspective view of the cooler shown in FIG. 1;

FIG. 3 is a front view of the cooler shown in FIG. 1;

FIG. 4 is a right side view of the cooler as shown in FIG. 1;

FIG. 5 is a rear view of the cooler shown in FIG. 1;

FIG. 6 is a left side view of the cooler shown in FIG. 1;

FIG. 7 is top view of the cooler shown in FIG. 1; and,

FIG. 8 is a bottom view of the cooler shown in FIG. 1.

The broken lines in the figures depict portions of the cooler that form no part of the claimed design.

1 Claim, 8 Drawing Sheets(56)
